UNITED STATES PATENT OFFICE.

DUDLEY SHAW, OF NEW YORK, N. Y.

ELECTROLYTIC CELL.

1,208,722.

Specification of Letters Patent. Patented Dec. 12, 1916.

Application filed June 22, 1915, Serial No. 35,518. Renewed October 11, 1916. Serial No. 125,087.

To all whom it may concern:

Be it known that I, DUDLEY SHAW, a citizen of the United States, residing at the city of New York, borough of the Bronx, Bronx county, in the State of New York, have invented certain new and useful Improvements in Electrolytic Cells, of which the following is a full, clear, and exact specification.

10 My invention relates to improvements in means for electrolytically producing gases, or separating fluids into their component gases, and the same has for its object more particularly to provide a simple, efficient and reliable electrolytic cell by means of which a fluid may be decomposed into its constituent gases, the said gases separately conducted from the cell to suitable containers.

Further, said invention has for its object to provide an electrolytic cell in which the removable or positive electrode may be readily removed without disturbing the electrical insulation thereof, and without disturbing the means which serve as the support for said electrode.

Further, said invention has for its object to provide an electrolytic cell in which the positive electrode, and the support to which it is secured can be readily removed from the cell, without disturbing or interfering with its electrical insulation, and without disturbing the particular means or member which serves to support said electrode.

Further, said invention has for its object to provide a cell in which all or the principal parts can be readily removed and replaced without disturbing the electrical or mechanical balance of the cell.

Other objects will in part be obvious, and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings forming part of this specification wherein like numerals of reference indicate like parts—Figure 1 is a central longitudinal section taken, substantially on the line 1—1 of Fig. 2, showing one form of electrolytic cell constructed according to, and embodying my said invention; Fig. 2 is a plan or top view thereof; Fig. 3 is a side view showing the positive electrode and the support therefor

jointly detached and partly removed from the cell, and Fig. 4 is a similar view showing the positive electrode with its support together with the diaphragm and its support, 60 as a whole, partly removed from the cell.

In the accompanying drawings I have shown my said invention as embodied in an electrolytic cell for obtaining hydrogen and oxygen by the electrolytic decomposition of 65 acid or slightly alkaline water.

In said drawings 10 designates a tank or container which may be of any suitable size or shape, and made of conducting material, such as cast or sheet metal. The cell 10 is 70 provided at its upper edge with a laterally extending flange 11 upon which is disposed a diaphragm support 12 having its edge conformed to the edge of the flange 11, of said cell 10. The said diaphragm support 12 is 75 preferably made of cast iron and is provided at its center with a rectangular opening having a sleeve portion 13 depending from the edge of said opening. The said sleeve portion conforms in outline substantially with the interior of the cell 10, but so, much smaller as to leave a material space between the outer sides thereof and the inner sides of the walls of said receptacle or container 10. 80

Upon the diaphragm support 12 is disposed a cover plate or top 14 which is sufficiently larger than the opening in the top 12 in order to form a closure for said opening. Bolts 14^a, 14^a, extend through the 90 cover plate 14, and the diaphragm support 12 and engage the flange 11 of the receptacle 10 to hold the parts in their assembled positions. Adjacent the ends of the cover plate 14 and intermediate the side thereof are 95 holes to receive bolts 14^b which engage the diaphragm support 12, as clearly shown in Figs. 1 and 2. The diaphragm support 12 is firmly secured at its ends to the flange 11 of the cell 10 by bolts 15, 15^a and the co-acting nuts 16, 16^a. The bolts 15^a also pass through one end of the cover plate 14. 100

17 denotes a diaphragm which is preferably made of asbestos fabric, and serves to keep the gases separated below the surface 105 of the electrolyte. The said diaphragm 17 is preferably made in the form or shape of a bag or sack and has its open upper end disposed about the depending sleeve 13 of the diaphragm support 12, and secured thereto by a flat metal strap or band 18. 110

19 indicates the positive electrode which

may be made either as a casting or of sheet metal and of a shape corresponding in cross-section substantially with the general outline of the cell 10, but so much smaller that the same may be easily inserted into and removed through the depending flange or sleeve 13 of the diaphragm support 12. The said electrode 19 is open at its top and bottom, and is provided at its upper end with a pair of transverse supporting members 20 which are secured at their ends to the opposite sides of the electrode 19. From the top of each supporting member 20 extends upwardly a stem 21 having a reduced portion 22 extending therefrom.

The cell cover or top 14 is provided with apertures in each of which is disposed a hard rubber bushing 23 having a flange 24 at its lower end, and above and below said flange 24 are disposed soft rubber packings 25, 25. The upper end of said bushing 23 extends through the cell top or cover 14, and has its projecting end surrounded by a soft rubber washer 26.

27 denotes a cap also made of hard rubber and provided with a central opening, and adapted to be passed over the upper reduced screw-threaded end 22 of the stem 21, and contact with the soft rubber packing 26 upon the upper surface of the top 14 and surrounding said reduced portion 22. Above the cap 27 is disposed a metal washer 28, and upon said metal washer is disposed a lock nut 29.

31, 31 denote nuts disposed upon the upper end of the reduced stem portion 22, and between said nuts 31, 31 is clamped an electric terminal 32.

33 denotes an oxygen gas outlet in the form of a tube which may be of any convenient size and length and extends through the top plate or cover 14 and into the space within the depending sleeve portion 13 of the diaphragm support 12, and 34 denotes a similar outlet for the hydrogen gas. The said outlet 34 also extends through the diaphragm support 12, and into the space between the outer side of the depending sleeve portion 13 thereof and the inner sides of the walls of the cell 10.

35 denotes an electric terminal which is secured directly to the cell 10 by clamping the same upon one of the bolts 15 intermediate the underside of the flange 11 and the nut 16 of such bolt.

36 denotes an eye-bolt secured to the cover plate 14 intermediate the stems 22 of the positive electrode serving as a handle whereby to raise said cover plate 14, and electrode therein when the cell is to be taken apart for inspection or cleaning.

The operation of the apparatus is as follows:—When the proper electrical current is supplied to the terminals 32, 35 a circuit will be completed and current caused to pass

from the terminals 32, or one of them, to the stems 21, positive electrode 19, through the electrolyte, and to receptacle 10, constituting the other electrode, and to the terminal 35, back to the source of electric energy, thus causing the decomposition of the electrolyte and the production of oxygen at the positive electrode, and hydrogen at the negative electrode. When it is desired to remove the positive electrode from the cell without disturbing the diaphragm support 12, and the diaphragm 17 thereon, it merely becomes necessary to remove the bolts 14^a, 14^b, 15^a which will permit of the raising of the cover plate 14 with the positive electrode secured theron without disturbing the said diaphragm support 12 and the diaphragm 17 secured thereto. If, on the other hand, it is desired to remove the cover plate 14 and the positive electrode 19 carried thereby, jointly with the diaphragm support 12 and the diaphragm 17 thereon, it merely becomes necessary to remove the bolts 15, 15^a, 14^a and grasp said parts by the eye-bolt 36, and raise the connected parts bodily out of the cell 10.

It is to be noted particularly that by means of my improved cell construction, I am enabled to remove the positive electrode and its support without disturbing the diaphragm or its support, and to remove the said electrode with its support, jointly with said diaphragm and its support, thus rendering the examination of the interior of the cell and its contained parts a simple matter, and preventing all liability of injury to the operator.

Having thus described my said invention, what I claim and desire to secure by Letters Patent is:—

1. An apparatus of the character described comprising a receptacle constituting an electrode, a support mounted upon said receptacle having an opening therein, a porous diaphragm secured to said support and registering with the opening therein, a gas outlet communicating with the interior of said receptacle outside of said diaphragm, a cover for sealing the opening in said support, a gas outlet communicating with the interior of said diaphragm, and an electrode secured to said cover and extending into said diaphragm, substantially as specified.

2. An apparatus of the character described comprising a receptacle constituting an electrode, a support mounted upon said receptacle having an opening therein, a sleeve member depending from said support, a porous diaphragm secured at its top to the sleeve member on said support, a gas outlet communicating with the interior of said receptacle outside of said diaphragm, a cover for sealing the opening in said support, a gas outlet communicating with the interior of said diaphragm, and an electrode secured to said cover and extending into said diaphragm, substantially as specified.

interior of said diaphragm, an electrode secured to said cover and extending into said diaphragm, means for securing said cover to said support, and means securing said support to said receptacle, substantially as specified.

3. An apparatus of the character described comprising a receptacle constituting an electrode, a support mounted upon said receptacle having an opening therein, a sleeve member depending from said support, a diaphragm secured at its top to the sleeve member on said support, a cover for sealing the opening in said support, an electrode secured to said cover and insulated therefrom and extending into said diaphragm, a gas outlet provided in said support, a gas outlet provided in said cover, means for securing said support to said receptacle, and means, independent of the means for securing said support to said receptacle, for securing said cover to said support, substantially as specified.

4. An apparatus of the character described comprising a receptacle constituting an electrode, a flange provided along the edge of said receptacle, a support disposed upon said receptacle and serving partly to close the same, means for securing said support to said flange; said support having a central opening therein, a sleeve member depending from the edge of said support, a diaphragm secured along its top to said sleeve member, a cover plate for sealing the opening in said support, an electrode disposed within said diaphragm, supporting means extending from said last-named electrode through the opening in said support and said cover plate and insulated from said cover plate, means for securing said cover plate to said support, means provided upon said cover plate for conducting gas from the interior of said diaphragm, and means provided upon said support and communicating with the interior of said receptacle exteriorly of said diaphragm for conducting gas therefrom, substantially as specified.

5. An apparatus of the character described comprising a receptacle constituting an electrode, a laterally-extending flange provided along the open portion of said receptacle, a support corresponding in outline with the outline of said flange, means for securing said support to said flange; said

support having a central opening therein, a sleeve member depending from the edge of said opening, a bag-shaped, flexible diaphragm disposed upon the depending sleeve on said support, means for securing said diaphragm to said sleeve, a cover plate for sealing the opening in said diaphragm, means for securing said cover plate to said support, an electrode disposed within said diaphragm, supporting members secured to said electrode and extending upwardly through said cover plate but insulated therefrom, a gas outlet secured in said cover plate and communicating with the interior of said diaphragm, and a gas outlet secured in said support and communicating with the interior of said receptacle exteriorly of said diaphragm, substantially as specified.

6. An apparatus of the character described comprising a receptacle constituting an electrode, a laterally-extending flange provided along the open upper end of said receptacle, a support corresponding in outline substantially with the outline of said flange, means for securing said support to said flange; said support having a central opening therein, a sleeve member depending from the edge of said opening and corresponding in outline therewith, a bag-shaped, flexible diaphragm disposed upon the depending sleeve on said support, a member embracing said diaphragm whereby to secure the same to said sleeve, a cover plate for sealing the opening in said diaphragm, means for securing said cover plate to said support, an electrode disposed within said diaphragm, supporting members secured to said electrode and extending upwardly through said cover plate but insulated therefrom, an outlet tube secured in said cover plate and extending into the sleeve member on said support, and an outlet tube secured in said support and extending into said receptacle exteriorly of said diaphragm, substantially as specified.

Signed at the city of New York, in the county and State of New York, this 21st day of June, one thousand nine hundred and fifteen.

DUDLEY SHAW.
